CLAIM

The ornamental design for a display map for vehicles, as shown.

DESCRIPTION

FIG. 1 is a front elevational view of a display map for vehicles showing my new design, with broken line showing for illustrative purposes only and forming no part of the claimed design;

FIG. 2 is a bottom plan view thereof;

FIG. 3 is a left side elevational view thereof;

FIG. 4 is a top plan view thereof;

FIG. 5 is a rear elevational view thereof;

FIG. 6 is a right side elevational view thereof;

FIG. 7 is a rear perspective view thereof; and,

FIG. 8 is a front perspective view thereof.
